UNITED STATES PATENT OFFICE

2,001,365

MINIATURE OR TOY BOAT

Frank L. Lindstrom, Bridgeport, Conn.

Application December 13, 1933, Serial No. 702,219

1 Claim. (Cl. 9—6)

This invention relates to miniature or toy boats such as are adapted to be made from sheet metal, and refers more particularly to the construction of the hull which, as designed, is made 5 from a single sheet of thin metal such as tin, copper or the like.

The purpose of the invention is to improve upon that class of invention disclosed in my prior Patent #1,673,701, dated June 12, 1929, 10 and as before stated is directed to the construction of the hull proper. It is obviously adapted to different designs of toy boats, irrespective of the particular form of motor or means, if any, for propelling the boat.

The object of this invention is to provide a 15 design of hull that can be formed of a single piece of sheet metal when suitably drawn, folded and swedged so that there remains only the central vertical seam in the point of the bow to be swedged, aside from the swedging necessary 20 for the attachment of the deck member to the top edge of the hull. This deck may be in the form of a single plain flat deck, as shown in the present embodiment, or may include a main 25 deck and a superstructure or double deck.

Since my present invention relates specifically to the formation of a hull of a boat, irrespective of the propelling mechanism employed, I 30 have herein purposely omitted illustrating and describing any form of motor and means of supporting the same.

With the above objects in view, I have shown 35 in the accompanying drawing a suitable embodiment of my invention, though it will be understood that the same is susceptible of such slight modifications as may come within the scope of the claim.

In the drawing

Fig. 1 shows a perspective view of a deck-covered hull of a small toy boat, formed of 40 sheet metal and constructed in accordance with my invention;

Fig. 2 shows a plan view of the said boat, 45 portions of the deck of the stern and bow being broken away, better to show the construction of the corner portions of the stern and the seam of the bow;

Fig. 3 shows a plan view of a portion of a 50 sheet metal blank from which the stern of the boat is formed;

Fig. 4 shows a perspective view illustrating the inside of the stern of the hull, before the 55 deck member has been applied; and

Fig. 5 shows a detailed cross section, taken on line 5—5 of Fig. 2.

From the description to follow, it will be seen that the boat, as shown in Figs. 1 and 2, is made of but two members, the hull being formed of one piece and the deck of another. The hull is drawn and formed in such a way as to make it possible to produce a relatively deeper hull than was possible in the old way by a simple drawing process. This is particularly true where it is necessary to form not only a relatively deep stern, but one having a substantially 5 straight vertical stern end portion.

Referring in detail to the characters of reference marked upon the drawing, 8 indicates the hull, by which I mean the entire lower portion of the boat illustrated in the drawing, and 9 represents the deck which is the flat top member whose edges 10 are turned over and under the outwardly turned edges 11 disposed outwardly from the sides and back of the hull in a way to form an absolute water-tight joint. 15 The deck member, as shown, is provided with but a single central opening 12 which may or may not be needed, according to such installations or additions to the toy, if any, as might be necessary.

The hull member, as formed, includes a comparatively flat bottom, though having a central longitudinal depressed keel-like portion 13. The upwardly bent portions of the blank 14 which form the sides 15 of the hull are brought together to form a sharp bow where a seam 16 is employed for uniting the forward ends of the two said side portions by turning one of the said edges 17 around and upon the other edge 18 and swedging them tightly together, as 25 shown at 16 in Fig. 2.

Referring now more particularly to Figs. 3 and 4, it will be seen that in the formation of the straight deep back end member or stern, I first bend the two side edge portions 19—19 40 of the blank 14 along the dotted lines 20—20 and then fold in the corner portions 21—21 along the dotted lines 22, 23 and 24, and simultaneously therewith fold up the back end portion 26 along the dotted line 27. This, as you will see, is done in a way to bring the folded corner portions 28—28 flat against the inner face of the vertical stern end, whereupon the hull is put into a suitable press where a blow is struck sufficient to flatten the folded portions 50 and to tightly press them together against the back and form neatly finished corners of the hull, making it absolutely water-tight.

Having thus described my invention, what I claim and desire to secure by Letters Patent is: 55

A toy boat comprising a hull made of a single sheet metal blank bent to form a relatively flat bottom, a bow, stern and sides, the top edges of the said sides and back being disposed out at substantially a right angle, and a sheet metal deck attached to the hull by having its edges turned down under and swedged to the angularly disposed edges of the sides and back, the

stern having a back formed at a right angle to the sides and bottom and having corner portions that are formed by folding in the corner portions of the sheet metal blank from which the hull is formed, and disposed flat against the inner wall of the stern portion of the boat. 5
